UNITED STATES PATENT OFFICE.

GUSTAV HANKE AND CHRIST LECKBAND, OF ADAIR, IOWA.

TRACE-CARRIER.

SPECIFICATION forming part of Letters Patent No. 585,438, dated June 29, 1897.

Application filed October 26, 1896. Serial No. 610,124. (No model.)

To all whom it may concern:

Be it known that we, GUSTAV HANKE and CHRIST LECKBAND, citizens of the United States, residing at Adair, in the county of 5 Adair and State of Iowa, have invented a new and useful Trace-Carrier, of which the following is a specification.

This invention aims to provide a trace-carrier of improved construction which will facilitate the attachment and disconnecting of the traces therefrom when required.

A feature of the invention is the provision of a device of the character set forth which will admit of the ends of the traces being coupled to the carrier by a snapping action and which ends when drawn upon with sufficient force will automatically disengage themselves, thereby enabling this operation to be accomplished in less time than is possible with 20 devices of like construction as generally provided.

Various other objects and advantages will suggest themselves as the nature of the improvement is disclosed, and to this and other 25 ends reference is to be had to the following description and the figures of the drawings here-to attached, in which corresponding and like parts are designated by the same reference characters.

30 The improvement is susceptible of various changes in the form, proportion, and the minor details of construction without departing from the principle or sacrificing any of the advantages thereof, and to a full disclosure of the invention an adaptation thereof is shown 35 in the accompanying drawings, in which—

Figure 1 is a top plan view of a trace-carrier constructed in accordance with this invention. Fig. 2 is a longitudinal section thereof. Fig. 3 is a perspective view of the base or main portion of the device. Fig. 4 is a perspective view of the spring carrying the lugs or projections to engage with the ends or cockeyes of the traces.

45 The base or main portion of the carrier comprises a plate 1, having end loops 2 for attachment therewith of the straps leading to the breeching and side loops 3 for connection thereto of the back-band strap. This plate 50 arches or curves slightly between its ends to obtain a comfortable fit upon the animal and

is formed with longitudinal flanges 4 at its sides and a transverse bridge 5 intermediate of its ends and joined to the longitudinal flanges. The sides of the bridge 5 are curved and merge into the inner sides of the flanges 4 and form therewith seats or spaces for the reception of the ends or cockeyes of the traces. The longitudinal flanges 4 decline from a point midway of their ends, and the top side of the bridge correspondingly declines and is slightly below the plane of the upper edge of the said flanges 4, so as to receive the spring 6, which is fitted upon the bridge and comes between the longitudinal flanges 4. The end portions of the spring 6 extend over the recesses formed at the ends of the base upon opposite sides of the bridge 5 and are supplied with tapering lugs or projections 7, which extend into the said recesses and engage with the ends or cockeyes of the traces and retain them in place when engaged with the carrier. These lugs or projections 7 are secured to the ends of the spring 6 in any substantial and firm manner either by rivets or in any way found most convenient. A bolt 8 or kindred fastening connects the spring 6 with the base and passes centrally through the spring and bridge portion of the plate. A ring 9 has connection with the head of the bolt or fastening and is a convenient means for tightening or loosening the bolt to vary the tension of the spring, whereby the tapering lugs or projections 7 are held against the plate with a greater or less force and whereby the resistance to the coupling and uncoupling of the traces from the carrier may be adjusted or regulated at will.

Having thus described the invention, what is claimed as new is—

A new article of manufacture, a trace-carrier consisting of a plate curving longitudinally and having end and side loops, and formed on its outer side with longitudinal flanges and an intermediate bridge, the opposite sides of the bridge curving outwardly from a central point and merging into the sides of the longitudinal flanges and forming end recesses, and the top of the bridge being in a lower plane than the top edge of the flanges, a longitudinally-curved spring fitted upon the bridge and between the said longi-

tudinal flanges, and having tapering lugs at its ends extending into the aforesaid recesses, and a bolt or fastening adjustably connecting the spring with the bridge and adapted to vary 5 its tension, substantially in the manner set forth for the purpose specified.

In testimony that we claim the foregoing as

our own we have hereto affixed our signatures in the presence of two witnesses.

GUSTAV HANKE.
CHRIST LECKBAND.

Witnesses:

JOHN CARNEY,
F. E. GATES.
